UNITED STATES PATENT OFFICE.

IVORY WEBSTER, OF WEST LIBERTY, IOWA.

MACHINE FOR LAYING DRAIN-TILE.

SPECIFICATION forming part of Letters Patent No. 329,246, dated October 27, 1885.

Application filed June 24, 1885. Serial No. 109,655. (No model.)

To all whom it may concern:

Be it known that I, IVORY WEBSTER, a citizen of the United States, and a resident of West Liberty, in the county of Muscatine and State of Iowa, have invented certain new and useful Improvements in Machines for Making Trenches and Laying Drain-Tiles; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved machine for making ditches and laying drain-tile in the same. Fig. 2 is a plan or top view of the same. Fig. 3 is a longitudinal vertical sectional view taken on the line $x-x$ in Fig. 2. Fig. 4 is a vertical transverse sectional view taken on the plane indicated by line $y-y$ in Fig. 3. Fig. 5 is a side elevation, and Figs. 6, 7, 8, and 9 are detail views of the cutting apparatus and the mechanism for regulating and controlling the same.

The same letters refer to the same parts in all the figures.

This invention relates to an improved combined machine or apparatus for making ditches or trenches, and for laying drain-tiles in the same automatically, and by a single passage of the machine over the field, provision being also made for covering the drain-tile thus laid by the soil originally removed by the formation of the trench, and without disturbing the position or condition of such soil; and it has for its object to provide a device of this class which shall possess superior advantages in point of simplicity, durability, and general efficiency.

With these ends in view the invention consists in the improved construction, arrangement, and combination of parts, which will be hereinafter fully described, and particularly pointed out in the claims.

In the drawings hereto annexed, A designates the main beam of the machine, to the rear end of which is secured the downwardly-extending furrow-opener B, which comprises in its construction the trench-forming and the tile-laying and covering mechanism. The said furrow-opener consists, practically, of a flat

wall or landside, C, inclined from the beam toward the furrow, and connected at its front and rear edges with the mold-board D, which is curved horizontally from the front to the rear edge, and between which and the landside a space, E, is thus left open. This space serves as a conduit for the drain-tiles, as will be hereinafter more fully set forth. By having a flat landside, as C, which bears against the solid earth, the machine is made to run steadier than where both sides are curved and has loose soil upon both sides, as has heretofore been done in machines of this class.

The front part of the sled R' is provided with apertures r'', in which are placed the uprights or standards T³, which support the rod T⁴, to which the power is applied for drawing the machine through the soil. By placing the standards in different holes the necessary direction is given to the sled for making the proper curve.

To the outer side of the mold-board, near the lower edge of the latter, is secured a flange, F, which extends from the front end of the said mold-board, first in an upward and then in a downward direction, either in a straight or in a curved line, although the latter is preferred, and the outer edge of which is connected by a wall, G, with the shoe H, or bottom of the mold-board. This flange serves to carry the sods and dirt which is loosened by the share, as will be hereinafter described, in the act of making the trench, over the tiles, and to deposit it in the original or in approximately the original position.

The main beam A of the machine has a transverse or laterally-extending beam, I, the ends of which are provided with slots J J, to receive the vertically-adjustable screw-threaded rods K K, the upper ends of which work in washers L L upon the under side of the said beam, and the lower ends of which are provided with flanges or collars M M, working in guides N N upon the longitudinal beams O O of the sled or runner P, which said beams are connected by means of cross-beams Q Q bolted thereto, or otherwise connected therewith.

The nose of the machine consists of the shoe R and an elliptical share, T, pivotally connected by means of the pin or bolt U. This shoe can be made of a single piece, or of two pieces, R³

and R' , as shown in Fig. 9, secured together by any of the well-known methods for doing such work. The rear portion of the shoe is provided with a rearwardly-extending lug, R' , 5 and perforations r' . The front part of the flange F is provided with two forwardly-projecting lugs, S , each of which is provided with a pin or projection, s . When the nose is put in place on the flange F , the lug R' fits between 10 the lugs S , and the projections s fit in the perforations r' , thus making a joint that will permit of a vertical motion of the front end of the nose, and one that has no projection on either the upper or lower surface, and one 15 which can be easily taken apart and put together.

The share T is a trifle wider than the shoe R , and has two perforations or slots, r' , one upon each side. Projecting through these 20 slots are the lower ends of the upwardly and laterally extending cutters V V , having notches v in their rear edges, which engage with the share, and the upper ends of which fit in inclined recesses W W in the cross-beam 25 I , the under side of which is provided with the adjusting-yokes Y .

Secured to the front side of the beam I is a transverse shaft, X , the ends of which have cranks Y , which work in notches Z in the 30 front sides of the upper ends of the cutters V . The shaft X is provided with a worm-wheel, A' , which is operated by means of the vertical screw B' , which is journaled in the beam I . By rotating the shaft X the cranks Y at the 35 ends raise or lower the cutters V , and with them the nose of the machine, thus causing it to make a shallow or a deep cut, as is desired.

By making the nose of the ditcher in two 40 pieces and having the share part of it pivoted to the shoe, as above described, and securing the cutters to it in the manner indicated, sufficient play is given to the parts to allow of the machine being drawn in a curved direction, as it 45 is not always desirable to run the ditch in a perfectly straight line.

C C' are a pair of bars or beams arranged longitudinally under the beams Q Q' , and connected with the latter by means of hooked 50 bolts D D' , or in any other suitable manner. The said beams C are connected by diagonal pivoted braces E , and their rear ends are provided with notches F' , in which are fitted the lower ends of the colter-arms V V . The bars C' 55 are also provided on their under sides, near their rear ends, with colters or cutters G , which precede the colter-arms and cut furrows in the soil in front of the latter, so as to enable them to pass more freely through the soil, and with 60 better results.

The main beam A of the machine is provided at its front end with a vertical slot, H' , in which a standard, I' , is arranged to slide vertically. The upper end of the said standard 65 is provided on its rear side with a bearing for a swiveled screw, J' , which works in a nut, K' , mounted upon trunnions L' , which have their

bearings in a slot, M' , formed horizontally in the front end of the beam A , intersecting the slot H' , and where the said trunnions are retained by means of pins or keys N' . The lower end of the screw J' is swiveled in a bracket, O' , upon the rear side of the vertically-adjustable beam I' . The lower end of the standard I' is formed or provided with a 75 gudgeon, P' , which is journaled in one of the cross-beams, Q' , of a sled, R' , the side pieces or runners of which, S , are provided on their under sides with sharp-edged impinging-boards T , which, when the device is in operation, will enter the soil, thus serving to guide the device and to hold it in the track in which it is drawn or guided.

The ends of the cross-beams Q' of the sled R' are connected with a cap-piece, U' , mounted 85 upon the upper end of the beam I' , by means of brace-rods V V' , as shown. A hinged diagonal or inclined brace, W' , connects the lower end of the beam I' with the cross bar or beam I , which latter is also connected with the main beam A by means of suitable braces, X . Braces Y' also connect the lower end of the brace W' with the rear beam, Q , of the sled P , and other braces and strengthening-fixtures may be employed whenever and wherever 95 they shall be deemed proper and necessary.

The main beam A of the device is provided at or near its rear end with a slot or recess, Z , from whence a chute, B^2 , of suitable construction, leads to the heel end of the mold-board, as will be plainly seen in the drawings hereto annexed. Said chute B^2 is provided with one or more adjustable shoes, C^3 , for the purpose of adjusting the said chute to tiles of various sizes.

From the foregoing description, taken in connection with the drawings hereto annexed, the operation and advantages of this invention will be readily understood without requiring any extended explanation.

The sleds which support the carrying-frame of the machine are vertically adjustable, as shown, thereby enabling the vertical adjustment of the furrow-opener to be effected with relation to the surface of the soil, and thus enabling a trench or ditch of any desired depth to be dug. The tile, which during the progress of the machine over the field is fed into the chute B^2 , is laid evenly in the bottom of the trench, which is curved or concaved for the reception of the said tile by the pressure of the heel end of the mold-board, which is cylindrical in shape, and the tile, as soon as it has been laid, is covered by the furrow-slice, which is carried over the flange F of the device, and which is thus restored to its normal position in the trench, with the exception of being raised or lifted by the tile, such being the most favorable condition for future cultivation of the soil.

It will be seen that, owing to the general construction and arrangement of parts, this device is especially adapted for turning curves, which is especially important in a

device of this class, as it is not always possible, or even desirable, to follow a straight line in laying the tile.

Having thus described my invention, I claim and desire to secure by Letters Patent of the United States—

1. In a combined ditching-plow and tile-laying machine, the herein-described furrow-opener, having a flat inclined landside, and 10 a mold-board which is curved from the front end to about the center, and thence recurved to the rear end of the said furrow-opener, substantially as and for the purpose herein set forth.

15 2. In a combined ditching-plow and tile-laying machine, the combination, with the furrow-opener, constructed and arranged substantially as herein described, of a shoe hinged horizontally to the front end of the said furrow-20 opener, and a share pivotally secured to the top of said shoe, substantially in the manner and for the purpose herein set forth.

25 3. In a combined ditching-plow and tile-laying machine, the combination, with the furrow-opener, of the shoe hinged horizontally to the front end of the same, a share pivotally secured to said shoe, and provided at the sides with slots, and the upwardly-extending colter-arms, having notches upon the 30 rear edge of the lower ends, substantially as herein described, for the purpose set forth.

35 4. In a combined ditching-plow and tile-laying machine, the combination of the main beam, the furrow-opener, a transverse beam secured to the main beam in front of the furrow-opener, a shaft journaled to the latter, and having a worm-wheel meshing with a 40 suitably-arranged screw, cranks at the ends of the said shaft, entering or engaging notches in the colter-arms extending upwardly from the cutter hinged to the front end of the furrow-opener, all arranged and operating substantially as and for the purpose herein set forth.

45 5. In a combined ditching-plow and tile-laying machine, the combination of the main beam, the furrow-opener, the hinged point

of cutter having upwardly-extending colter-arms, mechanism for the adjustment of the latter, a carrying-sled connected adjustably 50 with a transverse beam secured to the main beam by means of screw-threaded rods, and an adjustable frame secured to the said carrying-sled, the sides of said frame being connected by pivoted diagonal bars and equipped 55 with colters or cutters, substantially as and for the purpose set forth.

6. In a combined ditching-plow and tile-laying machine, the combination, with the furrow-opener having a flange upon one side 60 of the front end of which is provided with forwardly-projecting lugs having upwardly-extending projections upon their front ends, of a shoe having apertures and a rearwardly-projecting lug, and a share pivotally secured 65 to said shoe, substantially as and for the purpose set forth.

7. In a combined ditching-plow and tile-laying machine, the combination, with the furrow-opener and tile-laying mechanism, of a 70 vertical beam secured adjustably to the front end of said machine, and having its lower end swiveled or mounted pivotally in a carrying-sled the under sides of the runners of which are provided with sharp impinging-boards or 75 cutters, substantially as and for the purpose herein set forth.

8. In a combined ditching-plow and tile-laying machine, the combination, with the furrow-opener and tile-laying mechanism, of 80 a supporting-sled the front part of which is provided with holes or apertures, a vertical beam swiveled in said sled, and an upright rod or standard secured therein, and the hitching-rod passing through the upper end 85 of said standard, substantially as and for the purpose set forth.

In testimony that I claim the foregoing as my own I have hereunto affixed my signature in presence of two witnesses.

IVORY WEBSTER.
